UNITED STATES PATENT OFFICE.

CHARLES G. GILBERG, OF ROCKFORD, ILLINOIS.

PNEUMATIC ACTION.

1,226,326.

Specification of Letters Patent.

Patented May 15, 1917.

Application filed August 17, 1914. Serial No. 857,013.

To all whom it may concern:

Be it known that I, CHARLES G. GILBERG, a citizen of the United States, residing at Rockford, in the county of Winnebago and 5 State of Illinois, have invented a certain new and useful Improvement in Pneumatic Actions, of which the following is a full, clear, concise, and exact description, reference being had to the accompanying drawings, forming a part of this specification.

My invention relates to pneumatic actions, such for example as are used in player pianos and piano players. Actions of this kind, however, may be used for other purposes.

Prominent objects of the invention are to provide a simple and practical form of pneumatic action of the kind specified; to reduce the number of parts and obtain simplicity and inexpensiveness of construction; to prevent leakage; to obtain quickness and responsiveness and efficiency of action; and to secure the foregoing and other desirable results in a simple and expeditious manner.

While I have herein shown my invention as applied to a pneumatic action for a player piano, it will be understood that the invention is capable of other uses. In the arrangement shown, I provide a wind trunk 20 which is preferably of metal, and separate valve casings or holders which are also preferably of metal, and are desirably individual to the several pneumatics. The valve casings or holders are desirably attached to the 25 wind trunk by independent tubular members preferably made of flexible material, such as sections of rubber hose.

The individual valve members or casings 30 contain features of novelty and advantage 40 which will be more fully pointed out in connection with the drawings. Other features of novelty and advantage will also be pointed out.

In the accompanying drawings Figure 1 45 is a front elevation of a portion of a player piano pneumatic action mechanism involving the present invention;

Fig. 2 is an end elevation of the same;

Fig. 3 is a view partially in vertical section, and partially in elevation of a pneumatic and its associated valve casing or holder;

Fig. 4 is a cross section taken on line 4—4 55 of Fig. 3;

Fig. 5 is a vertical section of a portion of the mechanism shown in Fig. 1; and

Fig. 6 is a view of a detail of construction.

In Fig. 1 I show a structure involving side members 1 and 2 which are understood to be suitable supports located at the side 60 of the player piano. To these are secured cross bars or pieces 3, 4 and 5, which are secured to the uprights 1 and 2 by screws 6—6. These cross bars 3, 4 and 5 are preferably in the form of metal strips or angle 65 plates, as shown in Fig. 3 with horizontally extending flanges 7—7. Extending from side to side also are wind trunks 8—8, which are preferably in the form of tubular metal casings made out of brass or other suitable 70 material. These wind trunks are understood to be connected with a wind inducing apparatus, as for example by forming chambers 75 9 (Fig. 5) in the uprights 1 and 2, and connecting the same with wind inducing apparatus by means of a tubular connection 10 and a tube or pipe 11. Pneumatics 12—12 are arranged in rows behind supports 3, 4 and 5. These pneumatics are preferably connected with said supports and supported 80 by the same through the medium of lugs or strips 14—14 secured to the under sides of the lower leaves 12^a of the pneumatics, and also secured to the flanges 7 on the supports 3, 4 and 5, as by screws 15. Valve casings 85 or holding members 16 are arranged below the pneumatics 12, there being preferably one valve casing for each pneumatic, as well shown in Figs. 3 and 4. These casings are also desirably secured to the pneumatics as 90 by arms 17 formed on the casings and extended up and secured to the under leaves 12^a of the pneumatics by screws 18. These valve casings 16 are also connected with the wind trunks 8 preferably by flexible tubular 95 members 20, such as rubber hose sections adapted to fit over tubular projections 21 on the wind trunks 8, and also over tubular projections 22 on the individual valve casings. Each valve casing 21 has a duct or 100 passage 23 communicating with the interior of its associated pneumatic, and has also a valve chamber 24 to which said duct or passage 23 extends. Within the valve chamber 24 is a valve 25 having a stem 26 of cross-like cross section, as shown in Fig. 6. The valve 25 rests upon a valve seat 27 formed by the upper end of a sleeve or thimble 28. A pouch 29 is arranged below the valve stem 26. A disk 30 is arranged below the pouch 105 29 and has a threaded connection with an annular extension 31 formed on the bottom

of the valve casing. A disk 32 has a screw threaded connection with an upper annular ring or portion 33. The disk 32 has an opening or port 34 forming communication between the outside air and the valve casing 34. A tubular connection 35 preferably in the form of a metallic pipe section is connected with the under side of the disk 30 and this in turn is connected with a flexible 10 tubular member 36 preferably a rubber hose section, which is in turn connected by an elbow 37 with a tube 38 which is understood to be a tracker board tube and to extend to the tracker board.

15 When a music sheet perforation passes over the tracker board, allowing air to enter a tube 38, the pouch 29 is elevated, thereby elevating the valve 25 and closing the port 34 and opening the passage 23 to the duct 20 formed by the tubular member 22, whereby the pneumatic is put into communication with the wind trunk 8. Assuming the latter is in communication with a wind inducing apparatus continually maintaining a reduced air pressure in the wind trunk 8, the pneumatic 12 will be collapsed.

The pneumatics 12 are connected in some suitable way so that their operation is used in the musical instrument or other apparatus in which the pneumatic action is employed. As one arrangement I show the swinging leaves of the pneumatic provided with strips or lugs 40, (Fig. 2), and from these members 40 rods 41 are extended 35 downwardly and connected with levers 42 which are pivoted at 43 and connected at their other ends with other rods 44. These rods 44 extend upwardly and are provided with heads 45 which can be located so as to 40 strike the wippens or other parts of the piano action, thereby making the operation of the pneumatics 12—12 effective in playing the piano or performing other services. It will be seen that each pneumatic and its 45 valve mechanism are associated together independently of the other pneumatics and valve mechanisms, and that each pneumatic with its valve mechanism may be independently removed. This would be accomplished by removing the screws 15 for the pneumatic, and then detaching the valve casing 16 from the wind trunk 8, or from the flexible connector 20. Each valve mechanism may be separated from its pneumatic 50 if desired by removing the screws 18. The hinged portions of the pneumatics 12—12 are arranged above and supported by the wind trunks 8—8, as shown in Fig. 3.

It will be understood that changes and 60 modifications may be made without departing from the spirit of the invention.

What I claim is:

1. The combination of a pneumatic, a valve casing having a flange arranged 65 against the under side of the pneumatic,

and screws passing through said flange and a wind trunk located under and forming a support for one end of said pneumatic.

2. The combination of a pneumatic, a valve casing arranged against the under side 70 of the pneumatic, a wind trunk to which said valve casing is detachably connected, said valve casing being arranged near one end of said pneumatic, and said wind trunk being arranged at the opposite end of said 75 pneumatic, and said wind trunk forming a support for one end of the pneumatic.

3. The combination of a pneumatic, a valve casing having a flange arranged against the under side of the pneumatic, 80 screws passing through said flange, and a wind trunk to which said valve casing is detachably connected, said wind trunk being located underneath and supporting the hinged end of the pneumatic.

4. The combination of a pneumatic, a valve casing arranged below the pneumatic, a wind trunk and a connection leading to a tracker board, said valve casing having extensions leading to the pneumatic wind 90 trunk and tracker board respectively, said valve casing also having an extension arranged between the under side of the pneumatic and the valve casing, and a removable washer provided in said last named extension. 95

5. The combination of a pneumatic, a metallic valve casing located below said pneumatic and detachably secured to the pneumatic, said casing being provided with 100 a tubular projection, valve mechanism in said valve casing for controlling the action of said pneumatic, a metallic wind trunk provided with a laterally extending tubular projection, and a detachable tubular member connecting the tubular projections on said casing and said wind trunk. 105

6. The combination of a pneumatic and a valve casing having an upwardly opening air port provided by a removable washer, 110 said valve casing being located below said pneumatic with said air port close to the under side of said pneumatic, and being detachably secured in position, said valve casing being provided with a tubular side portion providing a passage to said pneumatic and extending upwardly from the side of the valve casing and terminating at the side of said air port. 115

7. The combination of a pneumatic, means for supporting said pneumatic at an end, means for engaging said support, said means being provided upon said pneumatic, and a valve casing detachably secured to the under side of said pneumatic and supported by the 120 same. 125

8. A valve casing having a removable pouch supporting member at its lower end and a valve above said pouch, and also having a duct or passage for connection with a 130

pneumatic opening upwardly at its upper end, said valve casing also having a laterally extending tubular projection for connection with a wind trunk.

5 9. The combination of a pneumatic, means for engaging and supporting the opposite ends of the pneumatic, a valve casing located underneath the pneumatic and supported by the same, and a tracker board tube located 10 underneath the pneumatic and extending to said valve casing.

10 10. The combination of a pneumatic, means for engaging and supporting the opposite ends of the pneumatic, a valve casing 15 located underneath the pneumatic and supported by the same, and a tracker board tube located underneath the pneumatic and extending to said valve casing, said valve casing being detachably secured to the under side of said pneumatic and said tracker board tube being detachably connected with the valve casing.

11. The combination of a pneumatic, means for engaging and supporting the opposite 25 ends of the pneumatic, a valve casing located underneath the pneumatic and supported by the same, a tracker board tube located underneath the pneumatic and extending to said valve casing, said valve casing 30 being detachably secured to the under side of said pneumatic and said tracker board tube being detachably connected with the valve casing, and a pneumatic connection for connecting the valve casing and wind 35 trunk, said connection being detachably connected with the valve casing.

12. The combination of a pneumatic, means for engaging and supporting one end thereof, a wind trunk located below and 40 supporting the other end of the pneumatic, and a valve casing located underneath and supported by said pneumatic.

13. The combination of a pneumatic, means for engaging and supporting one end 45 thereof, a wind trunk located below and supporting the other end of the pneumatic, and a valve casing located underneath and supported by said pneumatic, said valve casing being detachably secured to the under side 50 of said pneumatic.

14. The combination of a pneumatic, means for engaging and supporting one end thereof, a wind trunk located below and supporting the other end of the pneumatic, 55 and a valve casing located underneath and supported by said pneumatic, said valve casing being detachably secured to the under side of said pneumatic, and being also detachably connected to said wind trunk.

60 15. The combination of a pneumatic, means for engaging and supporting one end

thereof, a wind trunk located below and supporting the other end of the pneumatic, and a valve casing located underneath and supported by said pneumatic, said valve 65 casing being detachably secured to the under side of said pneumatic, and being also detachably connected to said wind trunk, and a tracker board tube connected with said valve casing and located below the same and also 70 below said pneumatic.

16. The combination of a pneumatic, means for engaging and supporting one end thereof, a wind trunk located below and supporting the other end of the pneumatic, and a valve casing located underneath and supported by said pneumatic, said valve casing 75 being detachably secured to the under side of said pneumatic, and being also detachably connected to said wind trunk, and a tracker board tube connected with said valve casing 80 and located below the same and also below said pneumatic, said tracker board tube being detachable from said valve casing.

17. The combination of a pneumatic, 85 a valve casing, a wind trunk, said valve casing and said wind trunk being spaced apart from each other longitudinally of said pneumatic, and a pneumatic connection between the wind trunk and the valve casing, both 90 said valve casing and wind trunk being positioned at one side of said pneumatic and between the ends thereof.

18. The combination of a pneumatic, 95 a valve casing, a wind trunk, said valve casing and said wind trunk being spaced apart from each other longitudinally of said pneumatic, and a pneumatic connection between the wind trunk and the valve casing, both said valve casing and wind trunk being located below said pneumatic.

19. The combination of a pneumatic, 100 a valve casing, a wind trunk, said wind trunk being located at one end of said pneumatic and supporting the same at said end, 105 and a member provided at the opposite end of the pneumatic for supporting said end, said valve casing being supported at one end of the pneumatic and having a connection with the wind trunk at its opposite end. 110

20. The combination of a pneumatic, a valve casing located below the pneumatic, a wind trunk, said valve casing and said wind trunk being spaced apart from each other longitudinally, also located below the pneumatic and at one side of said valve casing. 115

In witness whereof, I hereunto subscribe my name this 8th day of August, A. D. 1914.

CHARLES G. GILBERG.
